UNITED STATES PATENT OFFICE.

ROBERT KURZ, OF LEAVENWORTH, KANSAS.

SPARK-ARRESTER.

1,101,556.

Specification of Letters Patent. Patented June 30, 1914.

Application filed July 31, 1913. Serial No. 782,255.

To all whom it may concern:

Be it known that I, ROBERT KURZ, a citizen of the United States, residing at Leavenworth, in the county of Leavenworth and 5 State of Kansas, have invented certain new and useful Improvements in Spark-Arresters, of which the following is a specification.

My invention relates to spark-arresters 10 for locomotive or traction engine use, and has for its object to provide spark-arresting means that shall not clog or impede the draft through the stack, yet shall effectually perform its spark-arresting functions.

15 In order that the invention may be fully understood, reference will now be made to the accompanying drawing in which:

Figure 1 shows a vertical section, taken longitudinally of the locomotive, of a spark- 20 arrester embodying the invention. Fig. 2 is a front elevation of the same. Fig. 3 is a front elevation of the complete apparatus showing its relation to the boiler, and rail- 25 way. Fig. 4 shows a horizontal section, on line IV—IV of Fig. 1. Fig. 5 is a sectional detail view, on line V of Fig. 2.

1 indicates the smoke stack, which may be of the usual diameter and form, except that its upper end is cut off on a rearward and 30 downward incline, its highest point thus being at the front and its lowest point diametrically opposite. The line of termination is made concave, in order that the top of the stack may fit, but without contact, the 35 periphery of the smoke-impelled wheel 2. Said wheel is composed of a circular series of radially disposed sheet metal blades 3, rigidly mounted on and between a pair of side plates 2^a. Each side plate is provided 40 with a stub shaft 4 as shown by Fig. 5. Each stub shaft passes rotatably through a bearing 5, said bearings being mounted on a housing 6. Each shaft 4 is provided with a flywheel 7, the function of said wheels 45 being to steady the rotary motion of the arrester wheel 2. Preferably, the blades 3 are imperforate. Each of said blades is curved as at *a*, in such a way as to present a concave surface to receive the upwardly im- 50 pinging smoke and exhaust steam. Said blades are spaced apart at suitable distances to permit the passage of smoke diametrically through the wheel, as will be apparent from inspection of Fig. 1.

55 Housing 6 is only of sufficient breadth to freely contain the wheel, and extends at the

rear thereof to a point approximately over the axial line of the wheel. From this point the sides of the housing are cut down on vertical lines to about the level of the 60 wheel's axis. Between the housing and the stack, there is thus exposed to the atmosphere, about 90 degrees of the periphery and lateral surface of the wheel, said exposed surfaces being directly above the 65 smoke-stack. Diametrically opposite that portion of the wheel that receives smoke and exhaust steam from the stack, I provide a grating composed of a series of transverse baffles 8, the ends of which are secured to the housing side walls. The rear 70 housing wall 9 is cut away, as shown, to permit the escape of smoke between said baffles. Said baffles are, preferably, concaved toward the wheel, and are so arranged as to bar the passage of sparks while offering as little resistance as may be to the 75 escape of smoke. The front lower portion of the housing is concaved to fit the stack, and is secured thereto by angle-irons 10 and 80 rivets (or bolts) 12. At a suitable distance below the wheel, said housing is bifurcated 85 as shown at C, thereby forming two chutes, 14, which are extended downward around the boiler 15; thence downward to points 90 close to and above the rails 16, the bottoms of said chutes being open. The upper portion of the housing is secured to the lower portion by a hinge 17, so that said upper portion may be thrown open to admit the 95 wheel 2.

The operation is as follows: When the engine is standing, so that no steam is being exhausted, the draft through the stack 1 will pass to atmosphere between the blades 1 of the wheel, whether said wheel be in rotation or not. When the engine is in operation, the blasts of smoke and exhaust steam strike the wheel blades 3, thereby setting the wheel in rotation. This motion is made 100 uniform by means of the fly-wheels 7. The concave surfaces *a* retain sparks and cinders, while some smoke will pass upward through the front opening in the housing. By inertia of rotation, and by centrifugal 105 force, the sparks and cinders will strike the baffles 8 and fall therefrom, the descent being accelerated by the downwardly moving blades 3. The particles thus enter the chutes 14, from which they are discharged 110 upon the rails 16, my object therein being to increase the traction between said rails

and the drive-wheels. As aforesaid, a portion of the smoke will escape through the large forward opening of the housing 9, but a portion will also reach the atmosphere by passing through the wheel and between the baffles, 8. The locomotive's forward direction is indicated by an arrow on Fig. 1.

I am aware that spark-arresters comprising rotary elements have been devised herefore; and I do not claim, broadly, such devices. But it must be noted that in said prior devices the rotary element or elements were to be mounted entirely within the stack and fully inclosed thereby. Such constructions require special stacks, or expensive modifications and enlargements of existing stacks. Moreover, such constructions involve a serious degree of obstruction to the draft through the stack.

Having thus described my invention, what I claim and desire to secure by Letters Patent is:

1. The combination with a smoke stack, of a rotatably mounted smoke impelled element comprising a series of blades, the inner ends of said blades being separated so as to form a passage in the direction of the diameter of the element, each of said blades being bent away from and toward a radial line drawn from the axis of rotation.

2. The combination with a smoke stack, of a housing associated with the top of said stack, a wheel rotatably mounted in said housing and positioned to cover the upper end of the stack, said wheel comprising blades, the inner ends of which are separated so as to form a passage in the direction of the diameter of the wheel, and baffle plates carried by said housing and arranged adjacent the periphery of said wheel opposite the mouth of the stack.

3. The combination with a smoke stack, of a housing associated with the top of said stack, a wheel rotatably mounted in said housing and positioned to cover the upper end of the stack, said wheel comprising blades, the inner ends of which are separated so as to form a passage in the direction of the diameter of the wheel, baffle plates carried by said housing and arranged adjacent the periphery of said wheel opposite the mouth of the stack, said blades being

bent away from and then toward the radius of the wheel whereby the passage through the wheel is made of a tortuous shape. 55

4. A spark-arrester comprising in combination with a smoke-stack, a housing attached to the rearward upper portion of said stack, said housing having an open top portion directly above the stack; a rotatably mounted wheel positioned partly within said housing and above and exterior to the stack, one side of said wheel being in the path of discharge from the stack; said wheel comprising a series of radially arranged 60 blades, said blades being spaced apart to permit smoke to pass diametrically through said wheel.

5. A spark-arrester comprising in combination with a smoke-stack, a housing associated with said stack, a wheel positioned to cover the upper end of the stack and extending into said housing, said wheel comprising spaced, radially disposed blades; and a series of stationary baffles supported by 75 said housing about the periphery of said wheel, said baffles covering a portion of said periphery diametrically opposite the mouth of said stack; the entire top of said housing being open except for said baffles which 80 have spaces therebetween.

6. A spark-arrester comprising in combination with a smoke-stack, an open-topped housing attached to the rearward upper portion of said stack, a wheel rotatably mounted 85 in said housing and covering the mouth of said stack, said wheel having an open periphery and comprising a series of radially disposed spaced blades; and a series of spaced baffles arranged to cover a portion of 90 said wheel's periphery opposite the mouth of said stack, and said wheel and baffles being provided with smoke passages.

7. In combination, a smoke-stack having its mouth cut on a downward and rearward incline, a smoke-impelled wheel mounted in close proximity to and covering said mouth, and a support for the axis of said wheel. 95

In testimony whereof I affix my signature, in the presence of two witnesses.
